UNITED STATES PATENT OFFICE.

ALBERT LEROY TRESE, OF JENNINGS, OKLAHOMA.

COTTON-CLEANER.

No. 909,714.

Specification of Letters Patent.

Patented Jan. 12, 1909.

Application filed March 10, 1908. Serial No. 420,160.

To all whom it may concern:

Be it known that I, ALBERT LEROY TRESE, a citizen of the United States, and a resident of Jennings, in the county of Pawnee and State of Oklahoma, have invented a new and Improved Cotton-Cleaner, of which the following is a full, clear, and exact description.

This invention relates to cotton cleaners, and the object of the invention is to produce a device which will operate to clean raw cotton before ginning.

More specifically, the invention relates to devices for this purpose which employ pneumatic means for advancing the cotton through the machine in treating the same, and the invention concerns itself especially with providing means for ejecting the treated cotton from the device; the invention further provides means for treating the cotton with the boll to remove the boll and dirt, and is also adapted for treating the cotton without the boll when it is simply necessary to clean the cotton.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a vertical longitudinal section through the device; Fig. 2 is a vertical cross section on the line 2—2 of Fig. 1; Fig. 3 is a cross section on the line 3—3 of Fig. 1 near the middle of the device; Fig. 4 is a vertical section taken near the discharge end, on the line 4—4 of Fig. 1; and Fig. 5 is a vertical section through the forward portion of the device, and illustrating the same when adapted for simply cleaning the cotton without the boll.

Referring more particularly to the parts, represents the case of the device, which is adapted to be formed of sheet metal or similar material, in the form of a barrel or cylinder. The under side of this cylinder is formed with a longitudinally disposed channel 2 into which the refuse from the cotton passes. This channel is inclined so that it constitutes a chute, which delivers to a spout 3 on the under side of the case at the discharge end thereof.

Rotatably mounted in the barrel 1 there

is provided a horizontal shaft 4, which is adapted to be driven by a belt pulley 5. Within the barrel or case 1 there is provided a cylindrical screen 6 which is coaxial with the shaft 4, which extends from the forward wall or head 7 of the device to a point near the right-hand wall 8, as indicated. The parts beyond the end of the screen and near the right-hand wall 8 constitute a separator 9. At this point upon the shaft 4 there is rigidly mounted a fan 10 having radial blades 11, four in number, as shown in Fig. 4. The space in which this fan revolves is directly over the delivery spout 3 for the refuse, but is separated from the same by an auxiliary screen 12, as illustrated in Figs. 1 and 4. The space in which the fan 10 rotates is cut off from the screen 6 by a semi-circular head or diaphragm 13 having a vertical edge 14 disposed on the vertical diameter passing through the shaft 4, as indicated most clearly in Fig. 4. This diaphragm or head is disposed on the left-hand side of the separator, and this side of the separator is provided with an inclined delivery spout 15 which projects toward the left as shown. The vanes or blades of the fan 10 are disposed radially as shown, and the diaphragm 13 fits closely against the inner edges of these vanes, as indicated in Fig. 1. As shown also in Fig. 1, the channel or chute 2 communicates directly with the delivery spout 3, and it also communicates therewith through the interior of the separator 9 and through the screen 12. At the junction of the channel and the spout 3 I provide a horizontal baffle plate 16, the purpose of which will appear more fully herein-after.

On the upper side of the case 1 and at the end thereof remote from the separator 9, there is provided a receiving hopper or receiver 17, the lower edge whereof projects into the interior of the case so as to lie near the wall of the screen 6. One of the longitudinal edges of this hopper is provided with a bar or knife 18, the lower edge of which lies adjacent to the wall of the screen. The screen at this point is provided with an opening so as to permit cotton to be fed into the hopper 17 and pass into the interior of the screen, as will be readily understood.

On the shaft 4 just under the hopper 17 there is provided a rigid fan 20 which is

adapted to be longitudinally adjusted upon the shaft by means of a set screw 21, as shown in Fig. 1. This fan has arms 22 of reduced dimensions, which are provided at 5 their outer extremities with inclined blades 23, so that when the fan is rotating it tends to produce a draft or air current longitudinally from the receiving end of the device toward the delivery end. The outer edges 10 24 of the blades 23 are preferably beveled as shown, and as the fan rotates they pass quite close to the lower edge of the knife 18.

Between the separator 9 and the fan 20 the shaft 4 is provided with a plurality of 15 radially projecting arms or beaters 25.

The operation of the device will now be described: The spout 3 for the refuse is connected with a suction fan in the well-known manner so that a draft is produced 20 into the device through the hopper 17. In the position of the fan 20 illustrated in Fig. 1, the device is adapted for treating cotton with the boll. It will be observed that in this view the fan 20 is disposed at the right 25 of the hopper, so that the path of the right-hand edges of the blades lies near the right-hand wall of the hopper. When the cotton with the boll is fed into the hopper 17, the revolving blades of the fan strike the bolls, 30 break them up and separate them from the cotton. The inclination of the blades 23 then operates to produce a draft toward the separator and advances the cotton along the interior of the screen toward the separator, 35 and the cotton then comes into the path of the beaters 25. In this way the broken bolls and pieces of dirt become removed from the cotton and pass through the screen into the chute 2, where they find their way into the 40 refuse delivery spout 3. The current of air striking the baffle plate 16 is divided, so that a portion of it will pass into the separator. In this way the movement of the cotton from the screen into the separator is 45 facilitated. In this connection it should be understood that a draft or current of air is generated downwardly through the screen 12 from the separator into the spout 3. As the fan 10 rotates in the direction of the 50 arrow shown in Fig. 4, it will eject the cotton from the separator at the spout 15. In this connection, attention is called to the diaphragm 13, which together with the opposite wall 8, forms a trap to cut off the 55 spout 15 from the suction draft. The manner in which this trap is formed is illustrated in Fig. 4. It will be seen from an inspection of this figure that the blades of the fan are closed in between the head 8 and the 60 diaphragm 13 so as to prevent a backward flow of air through the spout 15 toward the spout 3.

When the device is to be used simply for 65 cleaning cotton which is free from bolls, the fan 20 is attached in the adjusted position

shown in Fig. 5; that is, it is near the outer side of the receiver or hopper 17. When in this position, a space is left at the right of the fan through which the cotton can pass into the screen without being beaten against the knife 18 by the blades of the fan. The fan in this case simply produces a current of air through the screen, but does not operate as a beater or breaker. It is, of course, essential that the width of the blades 23 of the fan, measured longitudinally of the shaft, should not be as great as the width of the hopper 17, so that the opening illustrated in Fig. 5 at the right of the fan, may be made.

Having thus described my invention, I 80 claim as new and desire to secure by Letters Patent:

1. A device of the class described, having a screen, a case surrounding said screen, means for advancing the cotton through said screen, beaters acting on the cotton within said screen, means for producing a draft through said screen, a separator formed in said case and having an outlet spout for the cotton, and a fan in said separator, said separator having side walls engaging the blades of said fan so as to form a trap and prevent an inward suction through said spout.

2. In a device of the class described, in combination, a case having a cylindrical screen disposed therein, a shaft extending axially through said screen and having beaters thereupon, means for forcing an air current through said screen, a separator at one end of said screen formed in said case, a fan 100 rotating in said separator, a diaphragm covering a portion of said fan and engaging the side edges of the blades thereof to form a trap, a delivery spout for the cotton leading from said separator and adapted to be cut off by the blades of said fan from continuous pneumatic communication with the interior of said case, and a second delivery spout through which an air current may pass from said case and carrying the refuse. 110

3. In a device of the class described, in combination, a case having a separator formed in the end thereof, a fan rotating in said separator, said separator having an ejecting spout for the cotton leading therefrom, means for advancing cotton into said separator, and a diaphragm forming an incomplete wall for said separator and engaging the side edges of said fan so as to form a trap cutting off said spout pneumatically from the interior 120 of said case. 115

4. In a device of the class described, in combination, a case having a substantially cylindrical screen mounted therein, a shaft rotatably mounted in said screen and having a plurality of beaters, a separator formed at one end of said case, a second screen at said separator, said case having an outlet opening for the refuse near said latter screen, and means for inducing an air current through 130

said cylindrical screen, said second screen affording means for inducing a current from said first screen into said separator to deliver the cotton thereto.

5. In a device of the class described, in combination, a case having a substantially cylindrical screen mounted therein, a shaft rotatably mounted in said screen and having a plurality of beaters, a separator formed at 10 one end of said case, a second screen at said separator, said case having an outlet opening for the refuse near said latter screen, means for inducing an air current through said cylindrical screen, said second screen afford- 15 ing means for inducing a current from said first screen into said separator to deliver the cotton thereto, said case being in communication with said outlet opening independently of said second screen, and a baffle plate tending 20 to direct the air current into said separator.

6. In a device of the class described, in combination, a case having a substantially cylindrical screen mounted therein, a shaft disposed axially within said screen and hav- 25 ing beaters, a separator formed in the end of said case beyond said screen, a fan rotating in said separator and having radially dis- posed blades, a diaphragm forming an in- complete wall cutting off a portion of the in- 30 terior of said separator from said screen, a delivery spout for the cotton leading from said separator adjacent to said diaphragm, a second screen formed in the wall of said sep- arator, a delivery spout in said case for the 35 refuse near said second screen, and means for inducing an air current through said screen toward said separator.

7. In a device of the class described, in combination, a case, a cylindrical screen 40 mounted therein, a shaft mounted axially within said screen and having beaters within said screen, said case having a receiving hop- per, and a fan attached to said shaft under said receiving hopper, said fan having blades 45 with edges passing near the lower edge of said hopper whereby said blades may break the cotton bolls fed through said hopper.

8. In a device of the class described, in combination, a case, a cylindrical screen 50 mounted therein, a shaft mounted axially within said screen and having beaters within said screen, said case having a receiving hop- per, a fan attached to said shaft under said receiving hopper, said fan having blades 55 with edges passing near the lower edge of

said hopper whereby said blades may break the cotton bolls fed through said hopper, and means for adjusting the position of said fan under said hopper.

9. In a device of the class described, in combination, a case, a cylindrical screen mounted therein, a shaft mounted axially within said screen and having beaters within said screen, said case having a receiving hop- per, a fan attached to said shaft under said receiving hopper, said fan having blades with edges passing near the lower edge of said hopper whereby said blades may break the cotton bolls fed through said hopper, and means for adjusting the position of said fan under said hopper, said fan affording means for inducing an air current through 65 70 said screen.

10. In a device of the class described, in combination, a case having a cylindrical 75 screen mounted therein, a shaft rotatably mounted in said screen and having beaters, said case having a hopper, a knife attached at the lower edge of said hopper, a fan having blades of less width than said hopper, 80 measured in the direction of the longitudinal axis of said screen, the outer edges of said blades passing near the knife to break the cotton bolls against the same.

11. In a device of the class described, in combination, a case having a receiving hop- 85 per at one end thereof on the upper side and having a delivery spout for the refuse on the lower side and at the other end thereof, a separator formed in said case over said de- 90 liver spout, a cylindrical screen disposed within said case, a shaft rotatably mounted in said case coaxially with said screen and having beaters, a fan mounted on said shaft under said hopper, a second fan disposed in 95 said separator, a diaphragm cutting off a portion of said separator from said screen, and a second spout for the cotton formed in said case adjacent to said diaphragm and at said separator, said case having a longitu- 100 dinal channel under said screen receiving the refuse from the cotton and communicating with said last named delivery spout.

In testimony whereof I have signed my name to this specification in the presence of 105 two subscribing witnesses.

ALBERT LEROY TREESE.
